UNITED STATES PATENT OFFICE.

IRA C. KOEHNE, OF DAYTON, OHIO.

DESIGN FOR A SCALE-LEVER.

SPECIFICATION forming part of Design No. 30,887, dated May 30, 1899.

Application filed May 8, 1899. Serial No. 718,030. Term of patent 14 years.

To all whom it may concern:

Be it known that I, IRA C. KOEHNE, of Dayton, in the county of Montgomery and State of Ohio, have produced a new and original Design for a Scale-Lever, of which the following is a specification, reference being had to the accompanying drawings, forming part of the same.

In the drawings, Figure 1 represents a top plan view of a scale-lever embodying my design; and Fig. 2 is a side elevation view thereof, these two views being deemed essential to fully illustrate my design.

The leading or essential feature of my design consists of a cross-piece near each end of the lever and having parallel portions upon each of said cross-pieces.

In said drawings, G and H represent a cross-piece near opposite ends of the lever I. J represents the parallel portions upon the cross-piece G. K represents the parallel portions upon the cross-piece H, and L represents a projection upon the lever I, said portions J and K and the projection L being parallel with each other. 25

What I claim is—

The design for a scale-lever, substantially as shown and described.

In witness whereof I have hereunto set my hand this 6th day of May, A. D. 1899.

IRA C. KOEHNE.
